UNITED STATES PATENT OFFICE.

FRANK C. RINSCHE, OF DETROIT, MICHIGAN, ASSIGNOR TO BURROUGHS ADDING MACHINE COMPANY, OF DETROIT, MICHIGAN, A CORPORATION OF MICHIGAN.

ADDING MACHINE.

Application filed June 19, 1920. Serial No. 390,212.

To all whom it may concern:

Be it known that I, FRANK C. RINSCHE, a citizen of the United States, residing at Detroit, in the county of Wayne and State 5 of Michigan, have invented certain new and useful Improvements in Adding Machines, of which the following is a specification.

The present invention relates to such uses of an adding machine as involve repeated operation thereof under the same setting, as for example when doing multiplication, and the object is to provide a substantially self-contained attachment applicable to a standard adding machine such as the well-known 15 Burroughs without involving any internal change whatever therein and without at all affecting its ordinary employment in the ordinary way. While being so applicable to such standard machine, the attachment supplies instrumentalities of simple character 20 and manipulation whereby automatic control may be had as to repetition in cycles of operation of the machine, predetermined in number, for example by numerical value of a 25 multiplier digit. The utility of the invention resides more especially in its applicability to an adding machine which is power driven, such as the well-known Burroughs machine carrying an electric motor and 30 equipped with a starting key or "touch bar" for closing a clutch and thereby causing the machine to be put through a cycle of operations. In carrying out the invention in the form here shown the attachment as a complete 35 unit is placed against one side of the machine and secured to its base and casing and a series of multiplier or multiple stroke keys thereupon become so related to the touch bar that depression of any one of these 40 keys will not only close the clutch to effect a cycle of operation of the machine the same as when the touch bar is employed in the ordinary way, but will cause repetition of the cycle automatically a number of times 45 corresponding with the designated value of the particular key in use and then automatic cessation will ensue. A simple flanged plate fastened to the legs of the touch bar supplies a shelf or ledge for the keys to act 50 upon, leaving the touch bar itself entirely free for ordinary uses, and provision is made for actuation of the counting and key-releasing element of the attachment by detachably

fitting an arm to the ordinary hollow stub shaft taking advantage of the latter's characteristics as a driving element to which an operating handle lever is applied when the machine is to be operated by hand instead of by power.

In the drawings which accompany and form part of this specification Fig. 1 represents in right side elevation an attachment embodying my invention applied to a Burroughs adding machine, sufficient of which appears for purposes of the illustration; Fig. 2 is a sectionalized right side elevation on a somewhat larger scale and including the main portion of the attachment and showing some of its parts broken away to disclose portions of others; Fig. 3 is a sectionalized top plan view showing a portion of the key-board and top panel of the adding machine casing, with touch bar broken away at one place and the attachment itself shown largely in section; Fig. 4 is a vertical cross-section taken substantially on the line 4-4 of Fig. 2; Fig. 5 is a detail perspective view of a certain detent element; Fig. 6 illustrates a limited number of the parts which appear in foregoing views, only the multiplier key of highest value being shown and the particular condition illustrated being that which obtains when that key has been fully depressed and is on the point of being released and restored to normal, the adding machine being at the middle of its cycle of operation; Fig. 7 shows a limited number of the parts including the multiplier key of lowest value and the condition here illustrated is that which obtains when said key has been fully depressed and the first of the two thus ordained cycles of operation of the adding machine is about to take place; Fig. 8 illustrates in perspective the differential counting and key-releasing element together with a fragment of the pawl which operates it; Fig. 9 is an axial section taken on the line 9-9 of Fig. 1; and Fig. 10 comprises two partially faced-out perspective views of parts shown in section in Fig. 9.

No space need be taken for description of the well-known Burroughs adding machine nor is any extended illustration of it at all requisite in order that anyone skilled in this art may clearly comprehend applicability thereto of the attachment which I am about

to describe. This attachment comprises an inverted U-shaped frame member whose legs 2 will be secured at their lower ends to the base 3 of the machine proper by thumb screws 4. The upper part 2^a of this frame member will be secured to the top bar of the right side panel of the machine casing by long screws 5 on which spacing collars 6 are placed as shown most clearly in Fig. 4. These screws 5 are preferably formed with reduced plain prolongations 5^a which occupy slots in the legs 7 of the familiar touch bar 8, the purpose being merely to prevent removal of the touch bar when the attachment is on the machine. The aforesaid frame piece in turn sustains a frame plate 9 secured to it by screws 10 with interposed spacing collars 11, and then there is a companion frame plate 12 spaced considerably away from the frame plate 9, being rigidly connected thereto by several cross-rods and nuts certain of which serve other purposes as will hereinafter appear. The relationship of these frame plates to one another appears quite clearly in Fig. 3 and the numeral 13 there designates certain of the just mentioned nuts, and 14 designates one of the connecting rods, the same and a similar rod appearing in cross-section in Fig. 2. Between the forward end of the frame plates 9 and 12 there is carried a pivot rod 15 for a gang of eight key levers which are designated respectively M², M³, M⁴, M⁵, M⁶, M⁷, M⁸, M⁹. There are spacing collars 16 between the outer ones of these levers and the respective frame plates, and thin spacing washers 17 between the different levers, and the latter are longitudinally slotted where they embrace the pivot rod as shown at 18 for the purpose of permitting not only a pivotal movement or swing of the levers upon this pivot rod but also for a longitudinal movement by which release of a depressed key is effected as hereinafter more fully described. Springs 20 applied to downwardly extending fingers 21 of these levers normally hold them all rearward and upward, the said fingers being in staggered relation as illustrated in Fig. 4 as a matter of convenience in assembling. Upstanding curved arms 22 of these levers are surmounted by key tops 23 which are inscribed with numerals 2 to 9. These numerals are on the sides of the key tops as illustrated in Fig. 2 merely for convenience of illustration, it being understood of course that they would actually be inscribed upon the top surfaces as usual and as in the case of the ordinary amount keys one row of which appears in Fig. 3. These upstanding lever arms or key stems 22, with the exception of the one surmounted by the 2 key, are variously offset from the levers as illustrated most clearly in Fig. 3, so as to bring the key-bearing portions all in line with each other, and each of these key stems, just below its top portion which receives the key, is formed with a laterally projecting finger 22^a which is down-turned at its extremity at a point adjacent the outer side of the touch bar 8. There is secured to the legs 7 of the touch bar a flanged plate 24 whose short flange lies under the touch bar and against said legs and may be secured thereto in any convenient manner, as for example by screws, and whose wide horizontal flange projects beyond the touch bar in a somewhat lower plane, and all of the key fingers 22^a over-hang this plate which thus supplies a ledge or shelf for them to act upon. It will be observed from Fig. 3 in particular that the fingers 22^a are so fashioned and disposed that there is a general convergence so that any one of them will act upon a middle area of the plate and therefore an even depression of the touch bar will be had whichever one of the keys is depressed. The key stems are confined against lateral deflection by the upper thickened part of the frame plate 9 and a flanged plate 25 secured to said frame plate by screws 26 with interposed spacing collars 27, and the key levers are likewise confined against lateral deflections by a series of division plates or bars 30 strung upon upper and lower rods 30^a anchored to the frame plate 9, and having clamping nuts 30^b on their outer ends and spacing washers 30^c between the plates. As already indicated, depression of any one of the keys causes its finger 22^a to act upon the plate 24 and thereby depress the touch bar 8 and this will have exactly the same effect as ordinary finger pressure upon said bar, that is to say the clutch of the motor will be closed and the machine set in operation. The purpose, however, being to cause the machine to execute a number of cycles of operation corresponding with the numeral upon the particular key depressed, the touch bar will be held down by a detent which comes into play whenever any key is depressed, and then the release of the key from the detent will be timed according to the value of the key. The detent is in the form of a yoke as most clearly shown by Fig. 5, the hub 31 of which is journaled between the frame plates 9 and 12 and the cross-bar 32 of which is in the form of a blade with a forward beveled edge. A spring 34 connects a stud on one side arm 33 of this yoke with a stud on the frame plate 9, normally holding the yoke forward with the upper surface of its cross-bar 32 at a sharp inclination. On the under side of each of the key levers there is a coacting edge 35, just rearward of which the lever has a notch 36. When a key is depressed the cam edge 35 of the lever bears against the upper surface of the bail cross-bar 32 and forces the bail rearwardly until the

point of the notched part passes the beveled edge of said cross-bar whereupon the latter springs into the notch, holding the key lever down as illustrated in Fig. 7. The 5 detent bail is common to all of the key levers and depression of one lever would have the effect of releasing another, provided the second lever could be depressed far enough which is not the case in all instances, as 10 hereinafter mentioned.

All of the key levers cooperate with a 15 rotary counting and key-releasing device which is in the form of a generally cylindrical block made up of a series of discs 40, each of which has a radial shoulder 41, these shoulders being stepped as most clearly 20 shown in Fig. 8. There are eight of the discs and so there are eight shoulders, one to cooperate with each of the key levers and the stepping of these shoulders in relation 25 to each other circumferentially of the cylindrical block is for the purpose of differentiating in the number of successive operations of the machine under control of the different keys. Thus in each operation of 30 the machine the cylindrical block is turned one step corresponding with the spacing between shoulders and if, for example, the 2 key has been depressed the block will only be 35 turned two steps, the first of which will bring the shoulder of the disc aligned with the 2 lever up to a shoulder of the latter, and the second of which steps will move that lever longitudinally and release it from the 40 detent bail, whereas in the case of depression of the 9 key the cylindrical block would be turned nine steps.

There is assembled with the disc 40 a 45 ratchet wheel 42, and there is mounted upon the frame plate 9 an actuating pawl 43. The latter lies against said plate and is confined and guided in its movements by a headed stud 44 secured in said plate and occupying a longitudinal slot 45 in the 50 pawl, and also by another headed stud 46 behind which the acting end of the pawl lies, as clearly shown in Fig. 2. There is a spring 47 which connects a stud on the pawl with a stud on the plate and serves 55 normally to retract the pawl so that it is out of engagement with the ratchet wheel. The lower end of the pawl carries a roller stud 48 which is acted upon by an operating arm (presently identified) so that upon 60 depression of a multiplier key the ensuing operation of the machine will cause the pawl to act upon the ratchet wheel 42 and turn the counting block so as to advance one of its shoulders 41 a step toward the shoulder of the depressed key lever and then in 65 the next ensuing operation of the machine the pawl will again act and advance the counting block another step. The key-lever-shoulders to which reference has been

each other as will appear most clearly from Fig. 3 where they are designated by the numeral 50. In the case of the levers whose keys are numbered from 2 to 5 inclusive these shoulders are at the rear end of the 70 levers whereas in the case of the remaining levers the shoulders occur at intermediate points. Of course the levers are vertically aligned with the shouldered discs 40 respectively. Normally cut-away or low peripheral portions of the discs are immediately below the shoulder portions of the levers, so that any one of the keys can be 75 fully depressed, that is depressed until it has been engaged by the detent bail and its shoulder 50 brought into a position confronting the shoulder 41 of the associated discs. The condition is illustrated in Fig. 7 where the 2 key is shown in depressed condition.

The counting and key releasing cylinder should only be operative when one of the 80 multiplier keys has been depressed and therefore it is put under control of the detent bail through the medium of a back stop pawl 60. It will be obvious that reciprocation of the actuating pawl 43 would not be effective to advance the cylinder 85 step-by-step unless some means were provided to detain the cylinder in the position to which said pawl advanced it. In the absence of any such means the pawl upon retraction would drag the cylinder back with it, besides which means are provided, as hereinafter described, which constantly 90 tend to reversely rotate the cylinder. Now, the back stop pawl 60 is mounted upon the plate 9 by a pivot screw 61 and is connected by a spring 62 with a rearwardly extending branch 33^a of one of the side pieces of the 95 detent bail. Said branch terminates in an up-turned nose 33^b which engages a short branch 60^a of the back stop pawl so that normally with the detent bail held forward by its own spring 34, the back stop pawl 100 is held out of engagement with the ratchet 105 42 and against a limit stud 65, as shown in Fig. 2. So long as this condition obtains reciprocations of the actuating pawl 43 are 110 idle, merely imparting a slight oscillatory movement to the counting cylinder. However, when any one of the multiplier keys is depressed it cams the detent bail rearward as before explained, with the result of pulling the back stop pawl into engagement with the said ratchet through the medium of the spring 62 and of course thereafter when the ratchet wheel is turned forward said back stop pawl will be thrown in behind a passing tooth and will therefore 115 perform its function of holding the counting cylinder as advanced by the actuating pawl. The condition is illustrated in Fig. 7, it being understood that the forward swing of the detent bail to engage its 120

beveled blade with the detaining notch of the key lever is a comparatively slight movement having no effect to impair the established coacting relationship between 5 the back stop pawl and the ratchet.

The means above referred to as constantly tending to turn the counting cylinder backward, and which do serve to restore that cylinder to normal after each series of multiplying operations, comprise a snail cam 70 sleeved upon the axle of the cylinder as most clearly shown in Fig. 8 and rigidly connected with the latter, (by a screw-rod 49 running through the discs 40 and the ratchet 42 to unify all) and an arm 71 having a roller 72 bearing upon said cam. A spring 73 connects said arm with a stud on the frame plate 12 so that the said roller is constantly pressed against the periphery 10 of the snail cam. The roller normally seats in a notch 70^a at the inner part of the snail cam thereby holding the cylinder in its proper normal position. As the cylinder is advanced by the actuating pawl 43 the 15 roller will first be forced out of the notch and will then ride upon the rising periphery of the snail cam and the spring 73 will constantly be tending to rotate the cylinder backward by reason of the pressure brought to bear upon the cam through 20 the roller. Therefore upon disengagement of the back stop pawl from the ratchet, which occurs when the depressed key lever is forced forward as shown in Fig. 6, and 25 then retraction of the actuating pawl, the counting cylinder will be rotated reversely to its normal position, the roller 72 riding upon the periphery of the snail cam and finally returning to its seat in the notch 30 of said cam whose forward side is sufficiently high to act as a stop preventing excessive rotation of the cylinder. The tail 35 70^b of the cam is up-turned sufficiently to guard against over-rotation in a forward 40 direction.

A brief résumé of the operation of the attachment will be now given. Assuming that the operation to be performed is one of multiplication, the multiplicand will be 45 set up on the regular key-board of the machine and the familiar repeat key will be set, and then one of the special keys will be depressed representing the unit digit of the multiplier. Assuming for the present that 50 this is the 2 key, the condition brought about will be that illustrated in Fig. 7 where the key lever is shown in engagement with the detent bail so that it is held down in position with its abutment shoulder 50 confronting the shoulder 41 of the associated disc 55 of the counting cylinder, the back stop pawl 60 having been engaged with the ratchet 42. Meanwhile the finger 22^a of the depressed key-lever will have operated the starting 60 bar 8 so that the adding machine goes

through a cycle of operation registering the multiplicand upon its numeral wheels, and the actuating pawl 43 will be advanced and retracted so that the counting cylinder will be turned forward one step. In the case of 70 the 2 key this one step movement will bring the disc-shoulder 41 up to the abutment shoulder 50 of the key lever. Inasmuch as the latter remains depressed and therefore still holds down the starting bar a second operation of the machine will immediately 75 ensue, so that the multiplicand will be again registered and added to itself and this, in the case of the multiplier digit being 2, completes the multiplication. In this second operation of the machine the actuating pawl 43 is again advanced and retracted and this time the disc-shoulder 41 acts upon the lever-shoulder 50 and pushes the lever forward; as permitted by its slot, so that said lever is 80 disengaged from the detent bail and will be restored by its spring. The bail itself will be swung forward by its spring and will disengage the back stop pawl from the ratchet and the spring-actuated arm 71 will 85 rotate the counting cylinder backward to normal position. Assuming further that the whole multiplier is 29, the amount keys will be released and the multiplicand set up over again one order to the left and the repeat-key again set, and then the 9 multiplier key will be depressed and the same multiplying operations will be gone through with 90 except that there will be nine operations of the machine. Fig. 6 illustrates the condition just as the ninth operation is completed with the machine at the middle of its cycle, the shoulder 41 of the associated cylinder disc having thrust forward the 9 key lever and disengaged it from the detent bail and 95 the latter having swung forward to normal and disengaged the back stop pawl from the ratchet, the latter, however, being for the moment held by the actuating pawl 43. The arm 71 stands ready to rotate the counting cylinder backward to normal when the actuating pawl 43 retreats as the final operation of the machine continues. To ensure escape of the depressed key lever from 100 the detent bail and certain restoration of the lever to normal, each lever has upon its lower edge just forward of its cam portion 105 35, a cam nose 80 adapted, when the lever is thrust forward, to ride upon a roller 81 journaled between the frame plates 9 and 110 12. The action is illustrated in Fig. 6 where the 9 key lever is shown thrust forward and forced slightly upward by the co-action between its cam nose 80 and said roller, so that the point of its detent notch 115 is above the beveled edge of the detent bail. The key lever is free to rise, and will do so, 120 the friction between the disc shoulder 41 and the abutment shoulder 50 not being sufficient to detain it, though if friction suffi- 125 130

cient to do so should be engendered at this point it would be immediately relieved upon retraction of the actuating pawl 43 and therefore the lever would only be momentarily detained.

Inasmuch as all of the abutment shoulders 50 are the same distance from the pivot rod 15, whereas the keys are different distances therefrom, and it is desirable to have substantial uniformity in degree of key-depression, there is gradation in the relationship between the key stem fingers 22^a and the touch bar plate 24 and correspondingly in the relationship between the under edges 15 of the key lever and the counting cylinder, increasing amounts of lost motion being allowed between said fingers and said plate as illustrated in Fig. 2 and correspondingly greater degrees of depression of key levers to bring their shoulders 50 into coacting relationship with the cylinder-shoulders 41. Thus normally the finger of the 2 key is closest to the plate 24 and the rear end of its lever is at the greatest elevation over the 25 counting cylinder, whereas the finger of the 9 key is spaced the furthest from said plate 24 and its under edge adjacent the shoulder 50 is at the least elevation over said cylinder.

It was before stated that certain of the connecting and spacer rods between the frame plates 9 and 12 served additional functions. One of them, designated 85, carries a rubber sleeve 86 to serve as a sound-deadening buffer for the key-levers when they are thrown up to normal position by their springs. The dimensions of the levers being exactly the same from their forward ends to the portions which are confined between the division plates 30, their top edges as well as their under edges will be slightly stepped in relation to each other, owing to the lost-motion-characteristic already described. Consequently the spacer rod 85 is conical in its middle portion and the buffer sleeve 86 takes a corresponding form, as clearly shown in Fig. 4 where the stepped relationship of the key levers also appears, all being in their normal position up against the under side of said buffer sleeve. A spacer nut 85^a is applied to the outer screw-threaded portion of the rod 85 between its conical part and the frame plate 12. Another of the connecting and spacer rods, designated 87, serves as a pivot for the spring-actuated cylinder-restoring arm 71, said rod being shouldered so as to properly confine the hub of said arm between which and the frame plate 12 a small spacing washer is interposed.

Passing now to the additional equipment for operating the pawl 43, the numeral 300 designates the regular hollow stub shaft which carries the familiar full stroke sector 311 which stub shaft has the usual clutch

formation to adapt it for positive rotative engagement with an operating handle. For the purposes of the present invention I provide an operating arm 88 equipped for similar rotative engagement with said stub shaft so that in the operations of the machine said arm will be oscillated and will drive the pawl 43. The outer portion of the arm is offset so as to bring its finger-like extremity into the plane of the pawl roller 48. Normally the arm stands in substantially horizontal position as shown in Fig. 1, spaced quite a distance away from said roller inasmuch as only a small portion of the stroke of the arm is required for the operation of the pawl. The arm is fitted over a reduced portion of a hub block 89 and clamped to the same by a thumb screw 90 and an interposed washer 91, said thumb screw engaging the threaded end of a rod 92 which runs through said hub. The latter has a clutch shoulder 89^a for engagement with the similar shoulder of the stub shaft and carries a clutch pin 93 to engage the opposite shoulder of said stub shaft, so that the hub and arm will be positively driven in both directions by said shaft. The hub is formed with a prolongation in the form of a split sleeve 96 whose tines are beveled at their ends on the inner side, and there is formed upon the rod 92 a cone 92^a to fit said bevels. A pin 92^b projecting from the cone occupies the slot between two of the tines of the sleeve to prevent the rod from rotating, and when the sleeve has been thrust into the hollow stub shaft and the clutch shoulders and clutch pin brought into coactive relationship, tightening of the thumb screw 90 draws the cone into the split sleeve and expands the same against the interior of the stub shaft securing the arm and its hub thereto against outward displacement.

The occasion for using a clutch pin on the hub of the arm instead of simply forming it with a complementary clutch segment is that when this operating equipment for the multiplying attachment is applied in place of an operating handle such as ordinarily used when a Burroughs motor driven adding machine is to be operated by hand, there should not occur the obstruction of the clutch-closing bar of the electric motor starting system. This bar is designated by the numeral 98 and it has an offset upstanding lip 98^a which ordinarily would be obstructed by the hub of the operating handle when the latter is interlocked with the hollow stub shaft. In the present instance, as best shown in Fig. 9, there is a space between the hub 89 of the operating arm and the low part of the outer end of the stub shaft into which space said lip can move when the bar 98 is lifted to close the motor clutch.

The above mentioned starting system re-

quires no detailed description since it is well known both through issuance of prior patents and through extensive public use. Reference may be had if desired to Vincent Patent No. 866,750 issued September 24, 1907. It will suffice to briefly review the working of the system in connection with the attachment of the present invention. Depression of the touch bar 8 by any one of the multiplier keys works the levers 99, 99^a to lift the vertical bar 98 through the medium of the spring 100 thereby swinging upward the arm 101 and releasing the clutch closing element within the gear and clutch casing whereupon the crank 102 is rotated and the drive shaft of the adding machine given its positive stroke. Roller stud 311^a on the full stroke sector 311 operates upon the branch 98^b of the bar 98 during this stroke to provide for the opening of the clutch upon completion of a single rotation of the crank 102 and this would occur in an ordinary operation of the adding machine, but in the case of depression of a multiplier key the touch bar is held down for one or more additional operations of the machine and therefore when the full stroke sector 311 makes its return stroke, under actuation of the customary power springs 103, the spring 100 which has been stretched by the thrusting downward of said bar, 98, will pull the latter up again so that the motor clutch will remain closed and a second operation of the machine will immediately take place.

It will now be seen that the object primarily stated will be thoroughly accomplished by the construction above described, the bulk of the equipment being applicable externally to the adding machine as a complete and self-contained unit and the actuating device being readily applicable to the stub shaft after the manner of applying an operating handle lever, in addition to which it is only necessary to attach the flanged plate to the legs of the clutch bar. Of course in the regular manufacture of the adding machine proper such plate could be put on ready for use whenever users of the machine should desire multiplying or multiple stroke attachments. At any rate the legs of the touch bars could be regularly prepared for the attachment of the plate and likewise the machine bases could be tapped for the reception of the thumb screws 4 so that no operations at all would have to be performed upon a machine already in the hands of a user in order to make ready for the mounting of the attachment upon his machine. In this connection it may be noted, as by reference to Vincent Patent No. 990,317, issued April 25, 1911, that the attaching screws 5 with their extensions 5^a would simply take the place of the screws shown in said patent designated 3656 1/4.

A cover 105 is put over the working parts of the attachment, being appropriately fashioned and finished so as to present a neat appearance. It is held in place by a number of screws 106 engaging tapped holes in the frame plate 9. The bottom flange of this cover is open at 105 for the passage of the pawl 43 as well as for the depending rear portion of the frame plate 9, the side flanges of the cover preferably extending past the edges of this frame plate and coming flush with the spacing collars 11 and up against portions of the U-shaped supporting frame piece 2, as shown in Fig. 3. The top flange of the cover is cut away throughout its length to accommodate the thickened part of the frame plate 9 and the flanged plate 25 and the connecting screws 26 and spacing collars, the horizontal flange of said plate 25 extending over the top flange of the cover as a closure for the opening therein and for finish purposes.

Mention was made at a previous point of the releasability of one multiplier key by another with certain restrictions. The latter have to do with release after one or more operations have been performed. Now manifestly any key can be fully depressed and any other already depressed key will be thereby released prior to the execution of an operation which steps the counting cylinder forward. Furthermore even if the error in key-selection is not discovered until after occurrence of one or more such operations, it can still be corrected by simply depressing the right key, provided the final operation has not taken place and provided the key erroneously depressed is not of higher value than the correct key and the cylinder has not advanced too far. For example, if the 2 key was erroneously depressed and the error noted after only one operation, any higher value key could be thereupon depressed, removing the shoulder of the 2 key from in front of the shoulder 41 of its cylinder-disc and interposing the shoulder of the higher value key in front of the shoulder of the associated disc to allow for a greater number of operations. And if the 3 key was erroneously depressed, instead of the 2 key and only one operation had ensued, the 2 key could then be depressed to limit the operations to two. But if the 4 key had been depressed instead of the 2 key and two operations had ensued, the 2 key could not be fully depressed because the high part of the associated disc would have been moved under the part of the 2 key-lever adjacent its shoulder 50.

It is to be understood that an attachment of the character described is not limited to use upon a Burroughs machine but is adaptable to other makes of adding machines, and it is further to be understood that the invention is not limited to the particular

structural features herein detailed but is susceptible of embodiment with various modifications.

I claim:

5 1. A multiple stroke unitary and self-contained attachment for adding machines comprising a supporting frame mountable upon the machine, means for securing the attachment to the completed machine, a set of keys
 10 carried in said frame for controlling the number of operations of the machine, detenting means for holding any key in set position, a counting and key-releasing member differentially related to the keys, and
 15 means for imparting step-by-step movement to said counting member, together with provisions for rendering said means operative for such purpose by the setting of a key, and for effecting release and restoration to normal of the counting member upon release and restoration of the set key.

2. A multiple stroke attachment for adding machines comprising a supporting frame mountable upon the machine, a set of keys
 25 carried in said frame, detenting means for holding any key in set position, a rotary counting and key-releasing member differentially related to the keys, and means for imparting step-by-step movement to said counting member, together with provisions for rendering said means operative for such purpose by the setting of a key, and for effecting release and restoration to normal of the counting member upon release and restoration of the set key.

3. A multiple stroke attachment for adding machines comprising a supporting frame mountable upon the machine, a set of key levers carried in said frame and having correspondingly located abutment shoulders, detenting means for holding any key-lever in set position, a rotary counting and key-lever releasing member having stepped shoulders to coact respectively with the key-lever abutment shoulders, and means for imparting step-by-step movement to said member; together with provisions for rendering said means operative for such purpose by the setting of a key-lever, and for effecting release and restoration to normal of the counting member upon release and restoration of the set key-lever.

4. A multiple stroke attachment for adding machines comprising a supporting frame mountable upon the machine, a set of key levers carried in said frame and having correspondingly located abutment shoulders, and being longitudinally movable and spring-held a spring-held detent blade in camming relationship to the key-levers and adapted to be displaced by any one of the latter when swung upon its pivot and to then detainingly engage such lever, a rotary counting member having stepped shoulders to coact respectively with the key-lever abutment

shoulders and disengage a key-lever from the detent blade by longitudinal thrust of said lever, and means for imparting step-by-step movement to said member; together with provisions for rendering said means operative for such purpose by the setting of a key-lever, and for effecting release and restoration to normal of the counting member upon release and restoration of the set key-lever.

5. A multiple stroke attachment for adding machines comprising a supporting frame mountable upon the machine, a set of keys carried in said frame, detenting means for holding any key in set position, a rotary counting and key-releasing member differentially related to the keys and having a ratchet, a reciprocating pawl coacting with said ratchet, a detaining pawl normally withheld from said ratchet by the key-detenting means, and means for restoring the counting member to normal.

6. A multiple stroke attachment for adding machines comprising a supporting frame mountable upon the machine, a set of key levers carried in said frame and having correspondingly located abutment shoulders, and being longitudinally movable and spring-held, a spring-held detent blade in camming relationship to the key-levers and adapted to be displaced by any one of the latter when swung upon its pivot and to then detainingly engage such lever, a rotary counting member having stepped shoulders to coact respectively with the key-lever abutment shoulders, and disengage a key-lever from the detent blade by longitudinal thrust of said lever, a ratchet on said member, a reciprocating pawl coacting with said ratchet, a detaining pawl normally withheld from said ratchet by said detent blade, and means for restoring the counting member to normal.

7. A multiple stroke attachment for adding machines comprising a supporting frame mountable upon the machine, a set of keys carried in said frame, detenting means for holding any key in set position, a rotary counting and key-releasing member differentially related to the keys and having a cam, means for imparting step-by-step movement to said member with provisions for rendering the same operative for such purpose by the setting of a key, and a spring-drawn lever coacting with the cam of the counting member to restore the latter.

8. A multiple stroke attachment for a motor-driven adding machine having a touch-bar, said attachment comprising a supporting frame for external application to the machine, a series of keys having fingers to operate upon the touch-bar, detenting means for said keys, and counting and key-releasing means rendered operative by the setting of a key.

9. A multiple stroke attachment for a motor driven adding machine having a touch bar and clutch-closing means operated thereby with provisions for re-clutch-closing 5 action under continued depression of the touch-bar, said attachment comprising a supporting frame for external application to the machine, a series of depressible keys with fingers to act on the touch-bar, detent- 10 ing means for said keys, a counting member, and means for moving the same step-by-step, with provisions for rendering said means effective by the setting of a key, for measur- 15 ing movement of said member by the value of the depressed key, and for releasing a set key by said member.
10. A multiple stroke attachment for a motor-driven adding machine having a handle clutch shaft, said attachment comprising 20 a detachable actuating arm equipped for rotative engagement with such shaft, a supporting frame, a series of keys to act upon the starting system of said machine, detenting means for the keys, and counting 25 and key-releasing means operated by said arm.
11. A multiple stroke attachment for a motor-driven adding machine having a touch-bar and clutch-closing means operated 30 thereby and including a reciprocating bar, and also having a handle clutch shaft, said attachment comprising a detachable actuating arm equipped for rotative engagement with such shaft, a supporting frame, a series 35 of keys to act upon the starting system of said machine, detenting means for the keys, and counting and key-releasing means operated by said arm; the latter having provisions for permitting full action of the 40 aforesaid reciprocating bar.
12. A multiple stroke attachment for adding machines comprising a supporting frame mountable upon the machine, a set of key levers carried in said frame and having cor- 45 respondingly located abutment shoulders, and being longitudinally movable and spring-held, a spring-held detent blade in camming relationship to the key-levers and adapted to be displaced by any one of the 50 latter when swung upon its pivot and to then detainingly engage such lever, a rotary counting member having stepped shoulders to coact respectively with the key-lever abut- 55 ment shoulders and disengage a key-lever from the detent blade by longitudinal thrust of said lever, and means for imparting step- 60 by-step movement to said member; together with provisions for rendering said means operative for such purpose by the setting of a key-lever, and for effecting release and 65 restoration to normal of the counting member upon release and restoration of the set key-lever; also provisions for translating longitudinal thrust of the lever into lateral movement sufficient for its escape from the 70 detent blade.
13. A multiple stroke attachment for adding machines comprising a supporting frame mountable upon the machine, a set of key levers carried in said frame and having cor- 75 respondingly located abutment shoulders, and being longitudinally movable and spring-held, a spring-held detent blade in camming relationship to the key-levers and adapted to be displaced by any one of the latter when swung upon its pivot and to then detainingly engage such lever, the latter having additional cam-formation, a frame-piece on which the same ride when 80 the lever is thrust longitudinally, a rotary counting member having stepped shoulders to coact respectively with the key-lever abutment shoulders and disengage a key-lever from the detent blade by longitudinal thrust of said lever, and means for imparting step- 85 by-step movement to said member; together with provisions for rendering said means operative for such purpose by the setting of a key-lever, and for effecting release and 90 restoration to normal of the counting member upon release and restoration of the set key-lever.
14. In a device of the class described, the combination of a set of keys, detent means for holding any key in depressed position, a rotary counting and key releasing member differentially related to the keys, and means for imparting step-by-step movement to said counting member, together with provisions for rendering said means operative for such purpose by the depression of a key, and for effecting release and restoration to 95 normal of the counting member upon release and restoration of the depressed key.

FRANK C. RINSCHE.
